UNITED STATES PATENT OFFICE.

NATHAN S. SCOVILLE, OF PERRY, NEW YORK, ASSIGNOR TO F. C. PRITCHARD, OF SAME PLACE.

MACHINE FOR EXTRACTING JUICE FROM POMACE.

SPECIFICATION forming part of Letters Patent No. 242,991, dated June 14, 1881.

Application filed May 7, 1881. (Model.)

To all whom it may concern:

Be it known that I, NATHAN S. SCOVILLE, of Perry, in the county of Wyoming and State of New York, have invented certain new and useful Improvements in Machines for Extracting Juice from Pomace; and I do hereby declare that the following is a full, clear, and exact description of the invention, which will enable others skilled in the art to which it appertains to make and use the same, reference being had to the accompanying drawings, which form a part of this specification.

Figure 1 is a side view of my improved press or machine for extracting juice from pomace. Fig. 2 is a side view of the opposite side of the same. Fig. 3 is a longitudinal vertical sectional view, and Fig. 4 is a vertical cross-section.

Corresponding parts in the several figures are denoted by like letters of reference.

This invention relates to an improved machine or press for extracting the juice from pomace, as in the manufacture of cider; and it consists in certain improvements in the construction of the same, which will be hereinafter fully described, and particularly pointed out in the claims.

In the drawings hereto annexed, A represents a suitably-constructed frame provided 30 at one end with bearings for the main shaft B, which may be operated by means of a crank, C, or by any suitable mechanism. A pawl and ratchet, D E, may be arranged, as shown, to prevent back motion of said shaft.

The main shaft B is connected by belts or bands F G, running on pulleys H I, with shafts J K, having pulleys L M for said bands. Shaft J is provided at its other end with a pulley, N, connected by a belt, O, with a pulley, P, upon 40 a shaft, Q, journaled upon brackets or uprights projecting upward from the frame, and carrying a roller, R, which is the grating or grinding roller of a mill, located above the press, and which may be of any suitable well-known 45 construction.

Journalized transversely upon the longitudinal top pieces of the frame, near the ends of the latter, are two flanged cylinders, S S, supporting an endless belt or apron, T, the construction of which will be hereinafter more

fully described. Said apron also travels under a flanged guide-cylinder, U, journalized upon the longitudinal bottom pieces of the frame, near the center of the latter.

The top frame-pieces, V V, are provided 55 near the center of the frame with uprights W W, in which are journalized a pair of elastic rollers, X Y, constructed like wringer-rolls, and arranged one above the other, the shaft Z of the upper roller, Y, being adjusted to slide 60 vertically in slots A' in the uprights, but forced in a downward direction by springs B', socketed in said uprights. The rollers X Y are geared together by pinions C', secured upon their respective shafts. The shaft D' of the 65 lower roller is connected by a twisted band, E', with a pulley, F', upon the end of the shaft K, mentioned above. Motion is thus communicated to the rollers X Y and to the endless apron T which travels between said rollers, 70 as shown.

The apron T is provided with a series of transverse pockets, G', which may be, and preferably are, constructed by fluting or plaiting the material of which the apron is composed, as clearly shown in Fig. 3 of the drawings, and stitching or otherwise securing the sides or ends.

In the flap under each pocket is secured longitudinally or transversely one or more flat 80 metallic springs, H', the effect of which is to keep the pockets partly open, and also to brace or stiffen the apron.

The shaft K is provided with a cylinder, I', having several longitudinal parallel rows of 85 brushes or bristles, J', which, in operation, are adapted to strike or sweep the face of the apron at the point of the latter which is at the time traveling or moving in a downward and rearward direction. Just above the same portion of the apron is arranged in suitable hangings a transverse rock-shaft, K', having beaters L' adapted to strike the apron, and provided with a crank or arm, M', connected by a spring, N', with the end of the frame, so as to be automatically drawn or forced in a downward direction.

O' is a transverse shaft, having a pulley, P', connected by a band, Q', with a pulley, R', formed upon the brush-cylinder I', or secured 100

upon the shaft K of the latter, from which motion is thus imparted to the shaft O'. The latter is provided with radiating wings or arms S', adapted, as shaft O' revolves, to strike an arm or spring, T', fixed upon the rock-shaft K', and thus raise the latter, with its beaters, against the tension of spring N', which latter, when the arm S' has passed, forces the rock-shaft back to its original position, causing the beaters to strike the endless apron a sharp quick rap.

Between the sides of the frame, under the elastic press-rollers X Y, is placed a pan or trough, U', for the reception of the fruit-juice, said trough being preferably provided with a spout, V'.

From the foregoing description, taken in connection with the drawings hereto annexed, the operation and advantages of my invention will be readily understood.

The pomace is discharged from the mill upon the endless apron, entering the pockets of the latter. As these pass between the press-rollers X Y the juice is extracted and filters through the apron into the trough or pan. As the apron descends the pockets are successively struck by the beaters L', which loosen the pomace-waste and permit it to be carried or swept off by the brushes upon cylinder I'.

My improved press is simple, inexpensive, durable, and easily operated, and it may, as will be seen, be operated continuously without any necessity for packing or otherwise handling the pomace.

Having thus described my invention, I claim and desire to secure by Letters Patent of the United States—

1. In a machine for extracting juice from pomace, the combination, with suitable press-rollers, of an endless apron having pockets to carry the pomace between said rollers, as herein described, for the purpose set forth.

2. In a machine for extracting juice from pomace, the herein-described endless apron, fluted or plaited to form a series of pockets, as and for the purpose set forth.

3. The combination, with the endless apron T, having transverse pockets G', of the flat springs H', arranged substantially as herein described, for the purpose set forth.

4. In a machine for extracting juice from pomace, the combination, with the endless apron having transverse pockets, of the elastic pressing-rollers, the upper one of which is capable of sliding vertically in its bearings, as herein described, for the purpose set forth.

5. The combination, with the endless apron having transverse pockets, of the rock-shaft K', having beaters L', and mechanism for operating the same, as and for the purpose set forth.

6. The combination, with the endless apron having transverse pockets, of the cylinder I', having longitudinal parallel rows of brushes or bristles J', and mechanism for operating the same, when arranged substantially as and for the purpose set forth.

7. As an improvement in machines for extracting juice from pomace, the combination, with suitable elastic pressing-rollers, of an endless apron having transverse pockets, the rock-shaft K', having beaters L', cylinder I', having brushes J', and suitable operating mechanism, all arranged and operating substantially as herein described, for the purpose shown and specified.

In testimony that I claim the foregoing as my own I have hereto affixed my signature in presence of two witnesses.

NATHAN SMITH SCOVILLE.

Witnesses:

W. W. BÜHRMANN,
L. E. CLEMERT.

It is hereby certified that Letters Patent No. 242,991, issued June 14, 1881, for an improvement in "Machines for Extracting Juice from Pomace," upon the application of Nathan S. Scoville, were improperly granted to F. C. Pritchard, as owner of the entire interest by assignment from Nathan S. Scoville; whereas it appears by assignments upon record in this Office that said F. C. Pritchard was assignee of one-half only of said Nathan S. Scoville's interest, and that the said Letters Patent should have been granted to said Nathan S. Scoville jointly with said F. C. Pritchard; that the proper corrections have been made in the files and papers relating to the case in the Patent Office, and are hereby made in said Letters Patent to make the title conform to the records of the Office.

Signed, countersigned, and sealed this 2d day of August, A. D. 1881.

[SEAL.]

A. BELL,
Acting Secretary of the Interior.
